UNITED STATES PATENT OFFICE.

ERNEST HUGO STRAUSS, OF CHICAGO, ILLINOIS.

TELEPHONE.

SPECIFICATION forming part of Letters Patent No. 733,296, dated July 7, 1903.

Application filed July 14, 1902. Serial No. 115,503. (No model.)

To all whom it may concern:

Be it known that I, ERNEST HUGO STRAUSS, a citizen of the United States, residing at Chicago, in the county of Cook and State of Illinois, have invented certain new and useful Improvements in Telephones; and I do hereby declare the following to be a full, clear, and exact description of the invention, such as will enable others skilled in the art to which it appertains to make and use the same.

My invention relates to certain improvements in electrical switches for telephones. It has for its object to guard against receiving any shock from the generator or from any foreign currents by touching the receiver hook or switch and the generator-crank. It is also characteristic for simplicity of construction and cheapness, is effective or perfect in action, and is compact in the arrangement of parts.

In the accompanying drawings, illustrating the preferred embodiment of my invention, Figure 1 is a side elevation thereof. Fig. 2 is a plan view. Fig. 3 is a detailed rear elevation of the same. Fig. 4 is a diagrammatic view showing the invention connected up in telephone-circuit.

Latitude is allowed herein as to details, as they may be changed without departing from the spirit of my invention and said invention remain intact and be protected.

In carrying out my invention I provide a long-arm switch-lever 1, usually called the "hook," for suspending in position the telephone-receiver, holding the parts in the bell-circuit. Said lever or hook is fulcrumed near one end in a bracket or post 2, suitably secured to a base. The fulcruming or pivoting of said lever is effected, preferably, by means of a pivot-bolt 3, passed through an aperture in said lever and through coincident apertures in the upper end of the principal member of said bracket or post and an offset or lateral branch or second member 2^a of the last-named part. Preferably arranged between the upper end portion of said post and its lateral member is a coiled or helical spring 4, with said pivot-bolt passing therethrough. Said spring has its ends secured to said post and lever, respectively, to effect the depression of one end of said lever when the receiver is removed therefrom, and the conse-

quent engagement of the contact-point nearer said end, presently described, with the telephone or talking circuit, as more fully disclosed presently. Arranged alongside or laterally of the post 2 and suitably secured thereto is a piece or block of hard rubber 5 or other suitable insulating material, having transverse slits therethrough to receive 6^a and into which are inserted and held contact-springs 6 6^a 6^b 6^c, preferably of German silver or of other suitable metal, for the respective circuits above named. The contact-springs 6 6^a are connected or wired up, as at 6^x 6^x, with the generator 7 and bell 8, preferably as shown, this constituting the bell-circuit. The contact-springs 6^a, &c., are wired or connected up, as at 6^b 6^b, via the electric battery 9 with the transmitter 10, the receiver 11, and generator 7, &c., thus constituting the telephone or talking circuit, the usual ground-wire connections being provided for in each of the foregoing circuits. The lower one of the contact-springs 6 has an upwardly bent or deflected portion or shoulder 6^c to provide for the effective engagement therewith of the upper contact-spring, as the last named is depressed by the preferably hard-rubber contact-point 12 of the lever or hook 1, as takes place in returning the receiver to said hook or lever, putting the parts into the bell-circuit. The two lower ones of the contact-springs 6^a, &c., are likewise provided with upwardly bent or deflected portions or shoulders 6^d to secure effective engagement therebetween and the uppermost contact-spring as it is depressed by a second preferably hard-rubber contact-point 12^a of the lever 1, as takes place under the action of the spring 4 in removing the receiver from said hook or lever, putting the parts into the telephone or talking circuit. The contact-points 12 12^a of the lever or hook 1 are arranged upon opposite sides of its fulcrum, thereby being adapted to effect, with the action of the spring 4, as will have been observed from the foregoing, the bringing alternately into service the bell-circuit and the telephone or talking circuit, as may be required.

From this construction and arrangement of parts it will also be noted that no part of any circuit or circuits is formed through the metal

base or supporting-post of the switch-lever thereon. Consequently no shock from the generator via that route or from foreign currents by touching said switch-lever and the 5 generator-crank can take place, as would be liable to occur and has been found in practice to result. This device is exceedingly simple, can be produced at the minimum expense, and is compact in arrangement.

10 Having thus described my invention, what I claim, and desire to secure by Letters Patent, is—

1. A switch-lever for suspending a telephone-receiver, in combination with contact-springs having engaging shoulders or projections, additional contact-springs adapted to be brought into engagement with said contact-spring shoulders or projections, and means carried by said lever comprising contact-points, one arranged upon each side of the fulcrum of said lever for effecting connection between the first-named contact-springs and said lever as it is actuated.

2. A switch-lever for suspending a telephone-receiver, in combination with contact-springs having engaging shoulders or projections, additional contact-springs adapted to be brought into engagement with said contact-spring shoulders or projections, a non-conductor carrying said contact-springs, and means carried by said lever comprising contact-points, one arranged upon each side of the fulcrum of said lever for effecting connection between the first-named contact-springs and said lever as it is actuated.

3. A switch-lever for suspending a telephone-receiver, having non-conducting contact-points arranged upon opposite sides of its fulcrum in combination with contact-springs having engaging shoulders or projections, and contact-springs adapted to be engaged by said non-conducting contact-points and brought into engagement with said shoulders or projections, and means for actuating said switch-lever, substantially as described.

4. A switch-lever for suspending a telephone-receiver, in combination with contact-springs having engaging shoulders or projec-

tions, additional contact-springs adapted to be brought into engagement with said contact-spring shoulders or projections, the support or bracket of said lever having a lateral non-conducting member supporting said contact-springs, and means carried by said lever for effecting connection between the first-referred-to contact-springs and said lever, as it is actuated.

5. A switch-lever for suspending a telephone-receiver, in combination with series of contact-springs, one series comprising two 60 springs, one having a shoulder or projection engaged by the companion spring, and the other series embracing three springs, the lower ones having three shoulders or projections, the lowermost shoulder or projection 65 being engaged by the intermediate contact-spring, and the shoulder of the intermediate spring being engaged by the uppermost contact-spring, and means carried by said lever for effecting connection therebetween, as it is 70 actuated, and the top contact-springs of the two series.

6. A switch-lever for suspending a telephone-receiver having non-conducting contact-points arranged upon opposite sides of 75 its fulcrum, in combination with series of contact-springs, one series comprising two springs and the other series three springs, the lower spring of the first-referred-to series having a shoulder or elevation engaged by the 80 upper spring thereof and the lowermost and intermediate springs of the latter series having like shoulders or projections, the shoulder of the lowermost spring being engaged by the intermediate spring, and the shoulder 85 of said intermediate spring being engaged by the uppermost spring, and a non-conducting support for said series of contact-springs, applied to the fulcrum-post of said lever.

In testimony whereof I affix my signature 90 in presence of two witnesses.

ERNEST HUGO STRAUSS.
